UNITED STATES PATENT OFFICE.

BENJAMIN HOUTS, OF JUNCTION CITY, KANSAS.

IMPROVEMENT IN BRIDGES.

Specification forming part of Letters Patent No. **222,499**, dated December 9, 1879; application filed August 30, 1879.

To all whom it may concern:

Be it known that I, BENJAMIN HOUTS, of Junction City, in the county of Davis and State of Kansas, have invented new and useful Improvements in the Construction of Bridges, of which the following is a specification.

My improvements relate to combined girder and suspension bridges wherein the girders rest at both ends upon the abutments and are sustained between the ends by cables.

The invention consists in combining girders and grooved abutments with cables, screw-bolts having nuts and hooks, suspenders, braces, and stays, as hereinafter fully described.

Figure 1 is a side elevation of a bridge constructed in accordance with my invention. Fig. 2 is a vertical cross-section of the same on line *x x*. Fig. 3 is a plan view.

Similar letters of reference indicate corresponding parts.

A A are the abutments of the bridge. *B B* are the girders, formed of the upper and lower string-pieces, *a b*, that rest upon the abutments *A*, the upper piece, *a*, upon which the flooring will be laid, being level with the top of the abutments.

The girders *B* are braced laterally by cross-girders *C*, that are connected at their ends to girders *B*, and these cross-girders *C* also support the inner string-pieces, *c*, intermediately of the abutments.

The girders *B* and their superstructure are supported between the abutments by side cables, *d*, that pass from the abutments beneath the hooks *e*, that are upon the ends of the suspender-plates *f*. The suspenders *f* are placed a suitable distance apart beneath the girders *B*, and each plate *f* is sustained by a separate cable, *d*, at each end. The hooks *e* are formed at the ends of screw-bolts, which pass through plates *f* and are retained by nuts beneath the plates. By these means the cables at each side and at each plate *f* may be tightened or loosened, as required. There are also inner cables, *d'*, that pass from the abutments beneath hooks *e'* on the cross-girders *C*.

The cables *d d'* all pass completely around

the abutments *A A*, the abutments thus forming the anchors of the cables. The strain on the cables from the weight is transferred to the abutment, and is opposed by the end-thrust of the upper string-pieces, *a c*, or by the whole girders *B*.

It will be seen that each length of bridge between the suspenders *f* is supported by a separate cable at each side, and the cables will be increased in number, according to the length of bridge.

The tops of the abutments *A* are formed with grooves *i* for the cables *d*, to retain them separate and prevent them from slipping sidewise.

The girders *B* are braced lengthwise by the crossed braces *k*, that are connected to the string-pieces *a b* of each girder.

The structure is stayed laterally by stay-braces *l*, that are connected to abutments *A* at *l'*, and extend diagonally beneath the bridge to the central suspender-plate *f*, to which the braces *l* are connected.

To stiffen the structure transversely there are braces *m*, that extend diagonally from the top of one girder *B* to the bottom of the other, and the cross-girders *C* are stiffened by braces corresponding to braces *k*.

I am aware that it is not new to secure tie-rods under adjustable clips of the vertical posts, or to secure cables to the abutments, or to sustain girders by the abutments, or to cross tension-rods in transverse planes, or to use crossing stay-rods, or to combine interior cables with cross-girders, or to use braces extending from the top to the bottom girders and crossing each other; but

What I do claim as new and of my invention is—

The combination, with abutments *A*, of cables *d d'*, screw-bolts having nuts and hooks *e e'*, suspenders *f*, braces *k*, and the stays *l*, all as shown and described.

BENJAMIN HOUTS.
